ATTORNEYS.

UNITED STATES PATENT OFFICE.

WILLIAM HUGERSHOFF, OF NEW YORK, N. Y.

ATOMIZER.

SPECIFICATION forming part of Letters Patent No. 495,249, dated April 11, 1893.

Application filed February 23, 1893. Serial No. 463,307. (No model.)

To all whom it may concern:

Be it known that I, WILLIAM HUGERSHOFF, a citizen of the United States, and a resident of New York city, in the county and State of New York, have invented certain new and useful Improvements in Atomizers, of which the following is a specification.

This invention relates to an improved atomizer for medicinal liquids and the like, in which by the simple shifting of a valve arranged in the side-piece of the air-tube, the atomizer can either be used for atomizing the liquid in throwing a spray or for throwing a jet; and the invention consists of an atomizer, the air supply tube of which is provided with a side-piece and a swiveled connecting piece to which the flexible tube leading to the pump is applied, said swiveled connecting piece being provided with an interior channel, so that the said channel can be placed in connection by the channels of the side-piece with the air supply tube and the receiving vessel, or only with the receiving vessel, according as a spray or a jet is to be produced.

In the accompanying drawings, Figure 1 represents a side-view of my improved atomizer. Fig. 2 is a side-view drawn on a larger scale, of a portion of the air supply tube with its side-piece and swiveled connection piece. Fig. 3 is a vertical longitudinal section on line 3 3, Fig. 4. Fig. 4 is a plan-view partly in horizontal section, on line 4 4, Fig. 2, of the air supply tube, side-piece, and connecting piece. Figs. 5 and 6 are vertical transverse sections, respectively on lines 5 5 and 6 6, drawn on a still larger scale than the preceding figures, and Fig. 7 is also a vertical transverse section, on line 6 6, Fig. 3, but showing the swiveled connection piece shifted, so as to shut the connection with one of the channels in the side piece of the air supply tube.

Similar letters of reference indicate corresponding parts.

Referring to the drawings, A represents a receiver for medicinal or other liquid which is to be ejected by my improved atomizing device. The receiving vessel A is closed by a suitable stopper B, in which the air supply tube C is inserted. Into the lower end of the air tube, located within the receiving vessel A, is screwed a suction tube D which is pro-

vided with one or more openings at its lower end. The upper end of the air tube is provided with an ordinary discharge tube C² having a nozzle C' with a central eduction opening C³. The air supply tube C is provided above the stopper B with a laterally extending side-piece E which is screwed into the side of the tube C and which is provided with two longitudinal channels e e', of which the channel e extends from the air supply tube to near the outer end of the side-piece and then extends at right angles to the surface of the rounded off enlarged end E' of the side-piece E, as shown clearly in Fig. 3. The second channel e' extends from the enlarged end of the side-piece E, to within a short distance from the inner end of the side-piece E and then extends at right angles to a channel e² that is arranged in the air supply tube C, and extends down to the lower end of the air supply tube, as shown likewise in Fig. 3. A connecting piece F is swiveled on the rounded off enlarged outer end E' of the side-piece E, the swivel connection being produced in the nature of a ball and socket joint and formed by springing the enlarged end of the connecting piece F while still in soft condition, over the rounded off enlarged end of the side piece E, whereby a very reliable and tight connection between the side-piece E and the connecting piece F is obtained. To the outer end of the connecting piece F is attached the flexible tube g, by which the connection with the valve bulb G is made, said bulb serving in the usual manner as the pump, by which the air is supplied to the receiving vessel A and the air supply tube C for the proper operation of the atomizer.

At the inside of the enlarged end of the connecting piece F is arranged a longitudinal channel f which on turning the connecting piece F on its axis, can be placed in connection with the inner end of the longitudinal channel e in the side piece E or moved side-wise of the same, so as to interrupt this connection, as shown respectively in Figs. 6 and 7. For the purpose of indicating the proper position of the channel f relatively to the channel e, an index mark m is arranged on the edge of the enlarged end of the connecting piece F, as shown in Figs. 4 to 7, which

index mark registers with an index mark *o* on the collar *E*² of the side-piece *E*, when the connection of the channels *f* and *e* is formed, but when the index marks are not in line with each other, then the connection between the channels *f* and *e* is interrupted. When it is desired to produce an atomizing action on the liquid in the receiving vessel *A*, so as to eject it in a spray, the index mark of the swivel connection piece *F* is set in line with the index mark of the collar *E*² whereby the connection between the channels *f* and *e* is produced, so that the air is conducted from the bulb through the air supply pipe to the nozzle of the discharge tube, and simultaneously through the channels *e'* *e*² to the interior of the receiving vessel *A*, so that air of a certain pressure fills up the upper part of the vessel *A*, and exerts thereby a pressure on the liquid so as to force it through the suction pipe toward the nozzle *C'*. The action of the air that is forced under pressure through the nozzle and the liquid that is forced under pressure of the air in the receiving vessel through the suction tube, produce an atomizing or spray action on the liquid, which spray action can be increased or decreased according as the channel *f* is made to register to a greater or less extent with the channel *e*. Whenever it is desired to produce a continuous jet of liquid the index mark of the swiveled connection piece is turned so that it is not in line with the index mark on the collar *E*² of the side-piece *E*, in which position the communication between the channels *f* and *e* is interrupted and thereby the air compelled to pass from the bulb through the channels *e'* and *e*² to the interior of the receiving vessel so that the liquid is forced in a continuous jet or stream through the discharge orifice *C*³. The mere shifting of the connecting piece produces thus either a spray

of the atomizer, which spray can be regulated within certain limits, or a continuous jet, as required for the proper application of the liquid.

Having thus described my invention, I claim as new and desire to secure by Letters Patent—

1. The combination, in an atomizer, of an air supply tube provided with a side-piece, said side-piece being provided with air channels, one channel communicating with the air supply tube, while the other channel is connected with a channel in the air tube terminating in the receiving vessel, and a swiveled connecting piece applied to the outer end of side-piece and provided with a channel which is adapted to establish or interrupt communication with the channel of the side-piece that leads into the air supply tube substantially as set forth.

2. The combination, with a receiving vessel, an air supply tube inserted in the same, a suction tube applied to the lower end of the air supply tube, a side-piece attached to the air supply tube and provided with two channels, one channel terminating in the air supply tube, while the second channel communicates with a channel located in the air supply tube parallel with the axis of the same, and leading to the receiving vessel, and a swiveled connecting piece applied to the outer end of the side-piece and provided with an interior channel that is adapted to register with the channel leading into the air supply tube, substantially as set forth.

In testimony that I claim the foregoing as my invention I have signed my name in presence of two subscribing witnesses.

WILLIAM HUGERSHOFF.
